UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed January 20, 1923. Serial No. 613,824.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

The invention relates to typewriting machines. More particularly, the invention relates to so-called billing machines in which provision is made for feeding a succession of bill-forms or form-sections in a continuous web, and in a plurality of plies ordinarily fan-folded, through a carbon-carrier, for interleavement of carbon-sheets with the web-plies; and in which the carbon-carrier, on a table attached to the platen-carriage at the rear of the latter, has fine-feed movement with the web toward the platen, and has movement rearward on the table for clearing carbons of the leading or written form-sections and for bringing them into interleavement with succeeding form-sections, at the completion of the writing on the leading form section. A machine of this general class is shown in United States Letters Patent to Wernery & Smith, No. 1,132,055, dated March 16, 1915. In the machine therein shown, the table is also provided, above the printing line, with a gage arm or extension thereon for receiving the leading or typewritten form-section of the web and for locating the leading edge thereof of preliminary to severance of such leading form-section from the rest of the web; and the platen is on a frame which may be swung by and with such gage and paper support to a position in which the grip on the carbons is relaxed to permit rearward movement of the carbon-carrier while the web-plies are held pinched to the gage; a knife edge being provided, against which the web may be drawn for severing the leading form-section therefrom. In the patent referred to, the carbon-sheets are held by blades which project into the fan-folds, in alternate or staggered relation, from opposite sides of the carrier.

It is often desirable that several of the plies of the leading form-section remain united to each other, after being severed from the rest of the web, until they are split apart, at their side edges, for distribution, mailing and filing. One of the plies,

however, is commonly an office record-sheet of all the individual bills, and it will be more convenient at times to file or keep this sheet integral than to cut the same into individual bill-lengths. If, however, this record-ply of the fan-fold web is to be left unitary, it must be split from the other plies so that the leading form-sections of the latter may be lifted from the record-ply in the operation of severing and removing them from the rest of the web.

An object of the invention is the provision of means for splitting the record-ply, lengthwise of the web, from the other plies, while maintaining the fan-fold connection of the other plies, one to the other, during the feed of the web through the machine. In the preferred form of the invention, the blade which holds to the carrier the carbon-sheet between the record-ply and the ply next thereto, is used as the means for splitting the record-ply from the other plies, and, for this purpose, is extended at its free end, beyond the line of the corresponding side edge of the web, to form a paper-splitter; the other blades, however, terminating at their free ends within the lines of the side edges of the web. Rearward movement of the carrier, therefore, causes the record-ply to be split from the others, but leaves the others as a fan-fold.

Another object of the invention is the provision of means whereby the record-ply may be fed over the paper-supporting arm or gage beyond the printing line, and beyond the leading edges of the other plies on such arm, without fouling; and whereby, without insertion of the fingers between the plies, all the plies may be pinched together against the front of the supporting arm or gage, with the record-ply folded around the end of such arm and against the rear face thereof, to provide a firm grip on all the plies; so that, in the operations involved in clearing the carbons from the leading form-section and in gaging or setting the web for writing on a fresh form-section, the record-ply may not be torn or injured.

Other features and advantages will hereinafter appear.

In the accompanying drawings,

Figure 1 is a top plan view of the platen-carriage, carbon-carrier-table, and attachments embodying the present invention.

Figure 2 is a view in side elevation, partly

cross-sectional, on the line 2—2 of Figure 1; the platen and the platen-frame being in normal or working position.

Figure 3 is a view similar to Figure 2, except that the platen-frame has been swung to carbon-releasing position, and the carbon-carrier-table is omitted.

A fan-fold web, shown as of four plies, 10^a, 10^b, 10^c and 10^d is led up from a suitable holder, over and around a rail 11, carried by brackets 12 on the rear of a carbon-carrier-table 13; guards 14 for the side edges of the web being adjustably secured by set-screws 15 to the rail 11. From the rail 11 the web passes forward to the carbon-carrier 16. The carbon-carrier comprises a plate 17, mounted to be slid forward and rearward on rails 18 on the table 13. Secured to the plate 17, at each side thereof, 20 is a block 19, having steps 20 thereon. Blades 21 are secured, each by one end thereof, to one of the steps 20. The blades on one of the blocks 19 are staggered or alternated, with respect to the blades on the other block; and the free ends of each of the blades, except the upper blade, terminate, as indicated at 22, in Figure 1, within the folds or side edges 23 of the fan-folded web. The free end of the upper 30 blade 21^a, as shown at 24, Figure 1, projects beyond the right-hand edge of the web, so that, when the carbon-carrier is moved rearward on the table, a knife-edge 25 on the blade 21^a will serve to sever the upper 35 ply of the fan-fold web from the next underlying ply. To each blade 21 and 21^a is secured the rear end of one of the carbon-sheets 26. These carbons are interleaved with the web-plies, and extend forward from the blades, as shown in Figure 2.

A rail 27 defines the forward end of the carbon-carrier-table, and this rail is secured to brackets 28 on the usual cross-piece 29 of the platen-carriage, so that the carbon-table 45 may have movements in letter-feed and return directions with the platen-carriage. The rear end of the carbon-table may be supported on a runway (not shown). From the carbon-carriage, the web-plies, with the 50 interleaved carbon-sheets, pass forward around a rail 30, carried by brackets 31 on the platen-carriage. Guards 32 on the carbon-carriage and other guards 33, adjustably secured to the rail 30 on the platen-carriage, serve to guide the side edges of the web. From the rail 30, the web and interleaved carbons pass downward around the platen 34 between the latter and the 55 usual paper table and apron 35 to the front of the platen; whence they are led upward across the printing line and over a front paper-table 36, carried by the platen-frame. The rear paper table and apron 35 carries the usual front and rear feed-rolls 37 and 38, in engagement with

the platen when the parts are in writing position.

The axle 39 of the platen is journaled in a frame consisting of side members 40, fixed to a rock-shaft 42, journaled in side 70 plates 43 of the platen-carriage; so that the platen-frame with the platen and front table 36 may be swung between Figure 2, or writing, position and Figure 3, or carbon-releasing, position. For effecting rotation of the platen in line-feed and reverse directions, the platen-axle 39 has fast there-to, at each end thereof, a pinion 44, in mesh with pinions 45, loosely mounted on the shaft 42; and the pinions 45, in turn, in 80 mesh with pinions 46, fast to stub-shafts 47, journaled in the side plates 43 of the carriage. The stub-shafts 47 carry the usual knobs 48; and the left-hand stub-shaft 47 carries the usual line-space-ratchet-wheel 85 (not shown). This ratchet-wheel is turned by a pawl (not shown), on a slide 49, having forward and rearward movement on the frame of the platen-carriage. One arm 50 of a bell-crank line-space lever serves to 90 throw back the slide 49 to effect a line-space movement of the platen through the ratchet-wheel (not shown), pinion 46, pinion 45, pinion 44 and platen-axle 39. The other arm 51 of the line-space lever carries 95 the usual finger-piece 52. The slide 49 and line-space lever are returned to normal position by a spring (not shown). Since the pinions 45 are on the rock-shaft 42, which serves as the pivot for the swinging 100 platen-frame, it follows that the platen, whether in Figure 2 or Figure 3 position, may be turned by the knobs 48, or by the line-space mechanism.

When the platen-frame is in Figure 2 105 position, it is supported at its rear by the rail 30, by means of fingers or extensions 53 on the side plates 40 of the swinging frame. The rail 30 is a rock-shaft, to which are made fast, one at each end thereof, hooks 54, for engagement with pins 55, set into the side plates 40 of the swinging frame. When the frame is swung from Figure 3 back to Figure 2 position, the hooks 54 are rocked back until the noses 110 56 thereof are free to be snapped over the pins 55, to lock the swinging frame in its Figure 2 position. This operation is effected by coil-springs 57, one on each end 115 of the shaft 30; each of these coil-springs 120 being secured at one end to the carriage-frame, and at its other end to a collar 58, fast to the shaft 30. The swinging frame is, therefore, automatically locked in writing position when swung down from Figure 125 3 position. For unlocking the swinging frame, to permit the same to be swung to Figure 3 position, one of the hooks 54 is extended upward in the form of a finger 58^a, having a finger-piece 59 thereon. 130

The front paper-table 36 is extended upward and rearward in the form of an arm 60; the end of which may serve as a gage for the leading edges of the web-plies. This web-supporting arm or extension 60 is preferably slidably adjustable on the table 36, so as to be set for web-forms of different lengths. For this purpose, it is in two sections, 60^a and 60^b, one of which is slotted 10 at 61, and the other of which carries pins 62, set into the slot. One of these pins may be in the form of a set screw or thumbscrew, threaded into the arm-section 60^b, and having a head 63 adapted to be turned 15 against the arm-section 60^a, to hold the latter in adjusted position. The upper end of the arm-piece 60^a carries a cross-piece 64, preferably of round or cylindrical surface, to prevent tearing or cutting of the 20 upper web-ply 10^a, led thereover. Carried by ears or brackets 65, fast to the rock-shaft 42, is the usual blade or cutter 66, against which the web-plies may be drawn in Figure 2 position, to sever the form- 25 lengths thereof.

In operation, after the typewriting has been effected on the leading form, said form is advanced to register its lower edge with the severing knife. The leading edges of the 30 leading forms are then pinched by the fingers against the extension-arm 60^a—60^b, the hooks 54 are released; and the platen-frame 35 is swung from Figure 2 to Figure 3 position, thus releasing the grip of the platen on the web and interwoven carbons. The web-ply 10^a is held tightly around the cross-piece 64, which serves as a snubbing bar, and the ends of the other plies are pinched to the gage-piece beyond the ends of the carbons, while the carbon-carriage, by means of 40 an arm 67 thereon, is thrust rearward, drawing the carbons rearward along, and relatively to, the web, to introduce the carbons into succeeding web-forms and to clear the 45 same of the leading typewritten form-sections. The rearward movement of the carbon-carrier causes the knife-edge 25 of the upper blade 21^a thereon to split the upper 50 ply 10^a of the fan-fold web from the other plies of the web. This accomplished, and with the written form-sections still gripped to the gage, the platen-frame is swung by the gage back to Figure 2 position. The 55 web-ply 10^a, which is the top ply at the carbon-carrier, but which is the underneath 60 ply on the front table 36, and which has been split, as aforesaid, from the other plies of the web, may then be released by the fingers, and the other plies, 10^b, 10^c and 10^d, gripped 65 together, drawn against the blade 66, to sever the same from the rest of their respective plies. The three lower plies, 10^b, 10^c, 10^d, as severed from the web, present a fan-fold and may remain in such fan-folded condition until themselves separated from one

another for distribution. The ply 10^a, uncut by the knife 66, will be left on the table 36, and will be fed therealong and over the upper end piece 64 of the gage-extension, as the succeeding form-section is written, and as 70 the web is stepped forward from one form-section to another. Any desired typewritten length of the ply 10^a, which length may include a considerable number of form-sections, may be allowed to accumulate beyond 75 the extension-end-piece 64; and, if desired, a receptacle may be provided for receiving such typewritten, unsevered length of the web-ply 10^a. Assuming, as indicated in Figure 2, that 80 one or more form-lengths of the ply 10^a have passed the end piece 64 of the gage-extension, and assuming that the leading forms of the other plies have been typewritten and engaged by the severing knife, and are ready 85 to be removed, the several plies of web are preferably gripped, as indicated in Figure 3, preliminary to being swung from Figure 2 to Figure 3 position. That is to say, one finger is placed on top of the gage, with the 90 plies all between the same and the gage, and the other finger holds the ply 10^a to the back of the gage, the latter ply being thus made to encircle the end rail 64 on the gage or extension. With the web-plies thus gripped, 95 the platen-frame is swung to carbon-releasing position.

To hold the web-plies against rearward movement with the carbons, it is thus unnecessary to insert any part of the hand 100 between the gage and that portion of the web which is past the rail 64. In gripping the ply 10^a around the end of the gage or supporting finger 60^a—60^b, the ply 10^a might be cut or torn if the gage or supporting finger presented a sharp or narrow end edge. The enlarged curved or cylindrical cross-piece 64, however, as above mentioned, eliminates such possibility of injury to the web. This cross-piece 64 may be present, and will 110 have the same function of protecting the ply 10^a, even when the several plies 10^a, 10^b, 10^c and 10^d are separate throughout their length, instead of being a fan-fold. It will be understood that, whenever, at any time, it 115 is desired to sever the typewritten portion of the ply 10^a from the rest of that ply, it may be drawn against the knife 66 in the same manner as are the other web-plies, and that it may be severed in the same operation 120 in which the other plies are severed, or in a separate operation.

Variations may be resorted to within the scope of the invention, and portions of the improvements may be used without others. 125

Having thus described my invention, I claim:

1. In a typewriting machine, a platen, means for feeding a continuous web to and around the platen, an arm beyond the print- 130

ing line extending lengthwise of the path of the typewritten portion of the web, and a cross-piece on the end of the arm for supporting the web clear of the rest of the apparatus; said arm being adjustable in length to accord to form-sections of different lengths in the web.

5 2. In a typewriting machine, the combination with a revoluble platen and a carbon-carrier shiftable toward and from the platen, of a web-slitter on the carbon-carrier to sever longitudinally a ply of a fan-fold web as the carbon-carrier is moved to the

rear, a transverse knife to cut off typed sections of the fan-fold web and serving as a 15 gage, and a transverse web-snubbing bar at the delivery side of the platen forming an anchorage for the gaged web wrapped there-over and resisting the backward drag of the slitter and the shifting carbons upon the 20 web, and preventing accidental shifting of the web away from its gaged position.

JESSE A. B. SMITH.
